(57)

CLAIM

The ornamental design for a censer, as shown and described.

DESCRIPTION

FIG. 1 is a perspective view showing my new design; FIG. 2 is a front elevational view thereof;

FIG. 3 is a side elevational view thereof;

FIG. 4 is a rear elevational view thereof;

FIG. 5 is a top plan view thereof; and,

FIG. 6 is a bottom plan view thereof.

The broken lines showing of portions of the censer are included for the purpose of illustrating the environmental structure and form no part of the claimed design.
